US00D992058S

(12) United States Design Patent (10) Patent No.: US D992,058 S
(45) Date of Patent: * Jul. 11, 2023

(54) FIGURINE

(71) Applicant: Qatar Tourism, Lusail (QA)
(72) Inventor: Edouard Chassaing, Paris (FR)
(73) Assignee: QATAR TOURISM, Lusail (QA)

() Term: 15 Years

(21) Appl. No.: 29/812,886

(22) Filed: Oct. 25, 2021

(51) LOC (14) Cl. 11-02

(52) U.S. Cl.

USPC D11/158; D21/603

(58) Field of Classification Search

USPC D11/127, 128, 133-137, 149-150,
D11/157-162, 184; D19/95-99;
D21/414-416, 418, 427, 428, 429, 627,
D21/630, 650-658

CPC A63H 3/02; A63H 3/04
